CLAIM

The ornamental design for a package shell for implanted device, as shown and described.

DESCRIPTION

FIG. 1 is a front and top perspective view of a package shell for implanted device, showing our design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof; and,

FIG. 7 is a bottom plan view thereof.
